GARMENT HANGER

Frank Le Roy, San Diego, Calif., assignor of one-half to James D. Robinson, San Diego, Calif.

Application December 29, 1944, Serial No. 570,386

2 Claims. (Cl. 223—96)

1

My invention relates to improvements in garment hangers, the primary object in view being to provide a hanger of simple form and inexpensive construction adapted to clamp several garments therein in suspended position to hang straight, each without interference with the other, and in unwrinkled condition, and which is especially designed for hanging on the usual rod and to facilitate removal of any selected garment therefrom without disturbing the other garments, or removing the hanger from the rod.

Other and subordinate objects are also comprehended by my invention, all of which, together with the precise nature of my improvements, and the advantages thereof, will be readily understood when the succeeding description and claims are read with reference to the drawings accompanying and forming part of this specification.

In said drawings:

Figure 1 is a view in side elevation of my improved garment hanger in a preferred embodiment thereof.

Figure 2 is a view in plan with the clamping bars swung into clamping relation.

Figure 3 is a similar view with the clamping bars swung out of clamping relation.

Figure 4 is a fragmentary view in side elevation showing the hanger hook swung out of the housing slots therefor.

Figure 5 is a view in transverse section taken on the line 5—5 of Figure 4.

Figure 6 is a view in rear end elevation.

Figure 7 is a view in front end elevation.

Figure 8 is a view in transverse section taken on the line 8—8 of Figure 2.

Figure 9 is a view in perspective of one of the fastener pins detached.

Figure 10 is a fragmentary view in plan of the rear end of one of the outer clamping bars.

Figure 11 is a fragmentary view in side elevation of said bar.

Figure 12 is a fragmentary view in plan of the rear end of one of the inner clamping bars.

Figure 13 is a fragmentary view in side elevation of the same.

Figure 14 is a fragmentary view in plan of the rear end of the other inner clamping bar.

Figure 15 is a fragmentary view in side elevation of the same.

Figure 16 is a fragmentary view in plan of the rear end of the other outer clamping bar.

Figure 17 is a view in side elevation of the same.

Reference being had to the drawings by nu-

2

merals, according to my invention, in the illustrated embodiment thereof, a garment hanger is provided comprising a pair of outer clamping bars 1, 2, and a pair of inner clamping bars 3, 4 intermediate the outer bars, all of said bars being pivotally connected together at rear ends thereof for lateral swinging movement relatively about a hinge pintle 5 into and from side-by-side clamping relation. A pair of substantially circular, flat hinge ears are provided on the rear end of each clamping bar 1, 2, 3, 4 and through which the pintle 5 extends axially, the ears of each bar extending crosswise of the bar and being constructed and arranged for assembly in 10 interlapping relation as follows: The pair of ears 7 on the outer bar 1 are spaced apart, in the plane of the bar, to fit between the pair of ears 8 on the other outer bar 2. The pair of ears 9 on the inner bar 3, and the pair 10 on the other inner bar 4 are spaced apart in each pair to interfit in interlocked relation with the outermost ear of each pair fitting between the pair of ears 7 of the outer bar 1. As shown, the pair of ears 7, 8, 9, 10 are offset, in different degree, 15 to one side of the bars for assembly concentrically and so that the bars 1, 2, 3, 4 may be swung into side-by-side relation. The pintle 5 is preferably formed with upset ends 11 countersunk in the ears 8 of the outer bar 1.

20 The inner bars 3, 4, are provided with front end, lateral bosses 12 on the outer sides of said bars rounded, as at 13, to reduce the number of sharp corners and formed in the inner sides thereof with semi-circular finger grip-forming sockets 14 for use in separating said bars 3, 4, 25 the bosses 12 forming oblique stop shoulders 15. The outer bars 1, 2 are formed with front, oblique end edges 16 fitting against said shoulders 15 to space the outer bars 1, 2 from the inner bars 3, 4 parallel in the clamping position of said bars. The inner bars 3, 4 when swung into 30 parallel clamping relation to each other are also slightly spaced apart, as will be clear. The described spacing of the bars 1, 2, 3, 4 into clamping relation thereof provides for clamping garments therebetween with uniform pressure throughout the clamped area of the garments.

35 A round-headed fastener pin 17 with a T-head free end 18 is rotatably extended, transversely, 40 through one boss 12 for extension of the end 18 thereof through a longitudinal slot 19 in the other boss 12 and turning of said end 18 crosswise of the slot 19 to fasten the inner bars 3, 4, together in clamping relation. A lock washer 20 45 on the pin 18, and the head of said pin, coact 50 with the slot 19.

with opposite sides of the boss in which the pin is mounted to prevent endwise movement of said pin.

A pair of fastener pins 21, 22 similar to the pin 17 are provided in the inner bars 13, 14 for co-action with slots 23, 24 in the outer bars 1, 2 to fasten the bars 1, 3 together in clamping relation, likewise the bars 2, 4.

A pair of oppositely turned hanger hooks 25, 26 are pivoted in longitudinal, upper edge slots 27, 28 in the inner bars 3, 4 each on a central transverse pin 29, 30 in said bars and whereby said hooks are swingable out of said slots over the usual rod 31 upon which such garment hangers are commonly hung. The slots 27, 28 are sufficiently deep to house the hooks 25, 26 when the latter are not in use, so that said hooks will not project from the bars when the hanger is packed or stored.

The manner in which the described garment hanger is operated and used will be readily understood. A garment may be clamped between the inner clamping bars 3, 4 and one between each of the outer clamping bars 1, 2 and the adjacent inner bar 3, 4 as the case may be. By unfastening the fastener pin 17, the inner clamping bars 3, 4 may be swung out of clamping relation for removal of a garment from between the same and while garments are still clamped between the outer clamping bars 1, 2 and said inner bars 3, 4. Likewise, either outer clamping bar 1, 2 may be swung out of clamping relation to the inner clamping bar complementing the same for removal of garments and while a garment is still clamped between the inner clamping bars 3, 4. The sockets 14 form convenient means for insertion of the finger therein to swing the inner clamping bars 3, 4 out of clamping relation. Obviously, by virtue of the pivotal mounting of the hanger hooks 25, 26, the same may be slid along the rod 31 when the inner clamping bars 3, 4 are moved out of clamping relation so that said hanger hooks will not interfere with free use of the inner clamping bars 3, 4.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. In a garment hanger, a pair of inner and a pair of outer clamping bars pivoted together at corresponding ends thereof for swinging into and out of parallel relation, the inner clamping bars complementing each other to clamp a garment therebetween, and the outer clamping bars each complementing one of said inner bars to clamp a garment therebetween, and means to fasten each outer clamping bar to its complementary inner clamping bar in clamping relation thereto, said inner bars having free ends with lateral reinforcement forming bosses thereon provided with finger grip forming sockets therein for use in swinging said inner bars.

2. In a garment hanger, a pair of inner and a pair of outer clamping bars pivoted together at corresponding ends thereof for swinging into and out of parallel relation, the inner clamping bars complementing each other to clamp a garment therebetween, and the outer clamping bars each complementing one of said inner bars to clamp a garment therebetween, means to fasten each outer clamping bar to its complementary inner clamping bar in clamping relation thereto, and means to fasten the inner clamping bars together in clamping relation, said inner bars having free ends with lateral reinforcement forming bosses thereon provided with finger grip forming sockets therein for use in swinging said inner bars, said bosses having oblique stop shoulders thereon, said outer bars having oblique free end edges for fitting against said shoulders to space said outer bars from the inner bars.

FRANK LE ROY.
